UNITED STATES PATENT OFFICE.

ZACHRY M. ABSHEAR, OF LOTHAIR, KENTUCKY.

AUTOMATIC COUPLER.

Application filed January 25, 1924. Serial No. 688,544.

To all whom it may concern:

Be it known that I, ZACHRY M. ABSHEAR, a citizen of the United States, residing at Lothair, in the county of Perry and State of Kentucky, have invented new and useful Improvements in Automatic Couplers, of which the following is a specification.

This invention relates to draft devices, particularly to car couplers, and has for its object the provision of a novel automatic coupler designed primarily for use upon mine cars though not necessarily limited to employment in such a capacity as it could be adapted for use on other rolling stock.

It is well known that the workmen frequently have their fingers and hands mashed and even often loose their lives in coupling together cars not only in mines but in other places, this condition arising from the necessity of going between the cars to effect coupling.

It is with these facts in view that I have designed the present device which is entirely automatic in action, the coupling taking place when the cars are simply brought together, release being effected by pulling upon a control element located at a distance.

An important object is the provision of a device of this character which will be simple and inexpensive in manufacture, highly efficient in use, durable in service and a general improvement in the art.

With the above and other objects and advantages in view the invention consists in the details of construction to be hereinafter more fully described and claimed and illustrated in the accompanying drawings, in which:

Figure 1 is a plan view of the two coupling members mounted on the adjacent ends of cars and showing them in engaged relation,

Figure 2 is a side elevation,

Figure 3 is a vertical section,

Figure 4 is a front elevation of one coupling member,

Figure 5 is a front elevation of the other.

Fig. 6 is a vertical section through one of the coupling members, and Fig. 7 is a detail horizontal section through the other.

Referring more particularly to the drawings the letter A designates the meeting ends of cars to be coupled. Mounted upon one car is a coupling device comprising a base plate 10 from which rise spaced flanges 11

55 reinforced by webs 12. This plate is formed with suitable holes for the passage of secur-

ing bolts 13 or the like which effect the necessary rigid mounting. Located between the flanges is a housing member 14 which is open at its bottom and which has its forward end provided with top and side flanges 15 and 16 which flare outwardly as shown so as to form guide means for the draft link to be described. At the rear ends of its sides, the housing 14 is formed with extensions or ears 17 through which passes a pintle pin 18 or its equivalent whereby the housing will be pivoted with respect to the base or plate 10. The top of the housing is formed with an elongated slot 19.

Pivoted upon the pin 18 is an elongated retaining hook 20 which extends within the slot 19 and which has its bill 21 extending downwardly across the housing with its end engaged upon the plate 10. The free or forward end of this hook is provided with a hole 22 within which is engaged a rod 23 or flexible member by means of which the hook may be lifted from a safe point.

Mounted on the meeting end of the other car A is a coupling member comprising a base plate 24 having holes for the passage of securing bolts 25. Rising from this base plate 24 is a block like body 26 having a horizontal slot 27 therein within which is engaged an elongated draft link 28 held in position by a coupling pin 29 which is vertically arranged and which fits within a suitable hole in the body.

To effect coupling, it is merely necessary that the two cars be brought together, whereupon the link 28 will enter the flared entrance end of the housing 14. As the link engages the bill 21 of the hook, the inclination of the bill will cause the hook to be swung upwardly so that the link may pass under it, after which the hook drops back to normal position to prevent retraction of the link. To effect uncoupling it is merely necessary that the operator pull upon the rod or other member 23 so as to lift the hook out of engagement with the link.

From the foregoing description and a study of the drawings it will be apparent that I have thus provided a simply constructed and consequently inexpensive coupling which will be positive and efficient in operation and which will be very safe in use so that accidents resulting from coupling cars will be entirely avoided.

While I have shown and described the preferred embodiment of my invention it is

of course to be understood that I reserve the right to make such changes in the form, construction and arrangement of parts as will not depart from the spirit of the invention 5 or the scope of the subjoined claims.

Having thus described my invention I claim:

- 10 1. A coupling device comprising, in combination, a supporting member carrying a draft link and adapted to be mounted upon an end of a car to be coupled to another, and a cooperating coupling member comprising a support having spaced upstanding flanges, an open bottomed housing pivoted between said flanges and having a flaring entrance, the top of the housing being slotted, and an elongated hook pivoted on said pivot and lying within said slot with its bill portion

extending downwardly across the housing and inclined rearwardly, the bill being 20 adapted to be engaged and lifted by said link.

2. In a car coupler, a coupling element 25 designed for co-operation with a draft link and comprising a supporting base having spaced parallel upstanding flanges, an open bottomed housing disposed between said flanges and having its bottom open and its top provided with a slot, an elongated hook disposed within said slot and having a bill 30 extending downwardly across the housing, and a pivot pin passing through said flanges, the sides of the housing and said hook.

In testimony whereof I affix my signature.

ZACHRY M. ABSHEAR.
